UNITED STATES PATENT OFFICE

110,009

DESIGN FOR A BADGE

Charles Howard Rowton, Palatka, Fla., assignor
to The American Legion Department of Florida,
Inc., Palatka, Fla., a corporation of Florida

Application April 4, 1938, Serial No. 76,291

Term of patent 14 years

To all whom it may concern:

Be it known that I, Charles Howard Rowton, a citizen of the United States, residing at Palatka, county of Putnam, State of Florida, have invented a new, original, and ornamental Design for a Badge, of which the following is a specification, reference being had to the accompanying drawing, forming part thereof, and wherein:

Fig. 1 is a front elevation of the badge, showing my new design; and

Fig. 2 is an edge elevation of the same.

I claim:

The ornamental design for a badge, as shown.

CHARLES HOWARD ROWTON.
